UNITED STATES PATENT OFFICE

CHARLES E. BEARDSLEY, OF WATERBURY, CONNECTICUT, ASSIGNOR, BY MESNE ASSIGNMENTS, TO THE BEARDSLEY AND WOLCOTT MANUFACTURING COMPANY, OF WATERBURY, CONNECTICUT, A CORPORATION OF CONNECTICUT

BATHROOM-SHELF BRACKET

Application filed August 19, 1925. Serial No. 51,147.

This invention relates to bathroom wall fixtures, and more particularly to an improved type of shelf bracket construction adapted to support the ends of a shelf.

5 The objects of this invention are to provide a device of this nature which will be simple in construction, inexpensive to manufacture, easy to install, compact, ornamental in appearance, very efficient and durable in use.

10 With these and other objects in view there has been illustrated on the accompanying drawings one form in which the invention may be embodied in practice.

15 Fig. 1 represents a top plan view, with parts broken away, of a shelf supported in a pair of the shelf brackets.

Fig. 2 is a front view of the same.

20 Fig. 3 is a side view of the left hand shelf bracket.

25 Referring now to the drawings in which like reference numerals denote corresponding parts throughout the several views, the numeral 10 indicates a shelf, which may be constructed from any suitable material such as glass. The shelf 10 is substantially rectangular in shape, has rounded corners 11, and is adapted to be supported at its ends by a pair of complementary shelf brackets 12 and 13.

30 Each of the brackets 12 and 13 comprises a horizontal flat base section 14, and a vertical flat rear wall-engaging section 15, said section 15 being semi-oval in shape and having three apertures 16 for receiving screws or other means by which the bracket may be attached to a wall, as of a bathroom.

35 In order to form a support for the front part of the glass shelf 10 to prevent it from sliding forwardly, each of said brackets 12 and 13 is provided at its front end with an upstanding lug 17, said lug being connected to the rear wall-engaging section 15 by a longitudinal rib 18, said rib being integrally joined to the bottom of the base section 14 and the front of the rear section 15, as clearly shown in Figs. 2 and 3.

40 The base section 14 of the left-hand shelf bracket is provided on its left-hand side with an upwardly extending lug 19, said lug being connected with the strengthening rib 18 of

said bracket by means of a transverse rib 19^a on the under side of the base 14. The rib 19^a is in alignment with the lug 19 and serves to increase the strength and rigidity of the bracket. The lug 19 serves to prevent the 55 glass shelf 10 from sliding to the left.

In order to prevent the shelf from sliding to the right, the right-hand shelf bracket 13 is provided with an upstanding lug 20 on the right-hand edge of the base 14, said lug 60 20 being similar in all respects to the left-hand lug 19, previously described. A short transverse strengthening rib 21 is also employed on the right-hand bracket in alignment with the lug 20 for connecting said lug 65 20 with the rib 18 of the right-hand bracket.

65 One advantage of the present invention is the extreme rigidity of the shelf brackets which is due to the use of both transverse and longitudinal strengthening ribs on the under 70 surface of the base sections thereof. This construction makes it possible to manufacture the brackets out of porcelain or other relatively frangible material with the minimum danger of breakage during use.

75 While there has been disclosed in this specification one form in which the invention may be embodied, it is to be understood that this form is shown for the purpose of illustration only, and that the invention is not to be 80 limited to the specific disclosure but may be modified and embodied in various other forms without departing from its spirit. In short, the invention includes all the modifications and embodiments coming within the 85 scope of the following claims.

Having thus fully described the invention, what is claimed as new and for which it is desired to secure Letters Patent is:

1. In a shelf bracket, a horizontal base 90 section, a vertical wall-engaging section, an inclined longitudinal rib integrally connected to the bottom of said base section along its entire length and integrally united with the front of said wall-engaging section, and an 95 integral transverse rib intermediate the ends of the base section extending from one side of said inclined rib to the lateral edge of said base section.

2. In a shelf bracket, a base section, a wall- 100

engaging section, said sections being integral-
ly connected by an inclined longitudinal flat
rib and a transverse rib located under said
base section and in front of said wall-engag-
ing section.

5 3. In a shelf bracket, a horizontal base
section having a front lug and a side lug
for engaging the front and end of a shelf
to prevent said shelf from moving forwardly
10 or laterally, said bracket having a vertical
wall-engaging section and an inclined rib in
the corner formed by said base section and
said wall-engaging section for connecting the
15 bottom of said base section to the front of
said wall-engaging section, said inclined rib
being in alinement with said front lug, and
an auxiliary strengthening rib extending
from said inclined rib to the bottom of said
side lug with which it is in alinement.

20 4. In a shelf bracket, a flat base section, a
wall-engaging section, said sections being
integrally connected by an inclined longitudi-
nal rib, and a transverse rib located under
25 said base section and in front of said wall-
engaging section, said ribs terminating in
upstanding lugs to support the front and side
of the shelf.

In testimony whereof, I have affixed my
signature to this specification.

30 CHARLES E. BEARDSLEY.
